(Cl. D91—3)

To all whom it may concern:

Be it known that I, Vincent R. O'Brien, a citizen of the United States, residing at St. Paul, Ramsey County, Minnesota, have invented a new, original, and ornamental Design for a Sink Spray, of which the following is a specification, reference being had to the accompanying drawing, forming a part hereof.

Fig. 1 is a side elevational view of a sink spray showing my new design;

Fig. 2 is a top elevational view of the same;

Fig. 3 is a front end elevational view of the same;

Fig. 4 is a bottom elevational view of the sink spray shown in Fig. 1.

I claim:

The ornamental design for a sink spray, sub-
stantially as shown.

VINCENT R. O'BRIEN.
